UNITED STATES PATENT OFFICE.

JAMES H. MATHESON, OF READING, PENNSYLVANIA.

BALL-PLACING DEVICE FOR TUBE MILLS.

Application filed April 4, 1922. Serial No. 549,486.

To all whom it may concern:

Be it known that I, JAMES H. MATHESON, a citizen of the United States, residing in Reading, Berks County, Pennsylvania, have 5 invented certain Improvements in Ball-Placing Devices for Tube Mills, of which the following is a specification.

My invention relates to certain improvements in tube forming mills, in which a 10 skelp is heated and is passed between a pair of rolls and over a ball so that the lapped edges of the skelp are welded to form a tube.

The object of the invention is to provide 15 mechanism for locating the balls in the proper position in respect to the rolls so that, when the ball rod moves forward, it will engage a ball and will carry it into proper position between the rolls in order 20 that a tube can be formed thereon.

This object I attain in the following manner, reference being had to the accompanying drawings, in which:

Fig. 1 is a vertical sectional view of my 25 improved mechanism for positioning balls in front of the rolls of a tube mill;

Fig. 2 is a plan view of the mechanism shown in Fig. 1;

Fig. 3 is a sectional view, similar to Fig. 30 1, showing the mechanism elevated and one of the balls in the act of passing into position in line with the rolls;

Fig. 4 is an end view of the mechanism when in the position shown in Fig. 3;

Fig. 5 is a plan view illustrating the location 35 of the mechanism in respect to the rolls;

Fig. 6 is a side view of a tube mill, showing the location of my improved mechanism 40 and the means for operating it from a distant point;

Fig. 7 is a perspective view of one of the balls and the end of the carrying rod;

Fig. 8 is a view of a modification of the 45 invention;

Fig. 9 is a view of the removable pocket member;

Fig. 10 is an enlarged view of a portion 50 of Fig. 6, showing the valve and the mechanism for operating the carrier; and

Fig. 11 is an end view of the mechanism shown in Fig. 10.

Referring to the drawings, 1 is a base. 2, 55 2 are standards supported by the base. On the upper ends of these standards are bearings 3. 4 is a carrier located between the

standards and pivoted at 5 to the bearings 3. This carrier is capable of being moved from the position illustrated in Fig. 1 to the position shown in Fig. 3. In the carrier is a 60 channel 6 for the balls *a*, shaped as shown in Fig. 7. Each ball is reduced at one end and has a hole *b* into which extends the end *c* of a ball-carrying rod *d*. The ball rests against a shoulder on this rod so as to resist the movement of the skelp as it is being formed into a tube between the rolls. At the outer end of the channel 6 of the carrier is a slideway 7 in which is a reciprocating slide 8. When in its lowest position, as shown in Fig. 1, the upper end of the slide is on a line with the channel so that the balls will roll onto the slide. When the carrier is raised, the slide is elevated, carrying with it the ball and when the 70 slide is in the position shown in Fig. 3, the ball rolls into a pocket 9 at the end of the carrier. This pocket, when the carrier is raised, is on a line with the rod *d* and with the opening between the rolls 10 and 11 75 of the tube forming mill. The pocket is of an even diameter throughout so that when the rod *d* moves forward, its extension *c* will enter the hole *b* in the ball and will carry the ball out of the pocket and into position between the two rolls, as in Fig. 5.

In order to move the carrier on its pivot, a cylinder 12 is provided, which is pivoted at 13 to a bearing 15. In this cylinder is 80 a piston having a rod 16, which is connected to the carrier by a pivot pin 17 so that, when fluid is admitted to the under side of the piston, the carrier will be moved from the position shown in Fig. 1 to that 95 shown in Fig. 3.

In order to raise the slide 8, it is connected to a lever 18 by a pin 19. The lever is pivoted to the carrier by a pin 20. The opposite arm of the lever extends between two 100 bearings 21 and 22. These bearings are so arranged on the standards 2 that, when the carrier is raised, the lever is turned on its pivot and the slide 8 is projected to the position shown in Fig. 3. When pressure is 105 exerted on the upper side of the piston, the carrier drops to the position shown in Fig. 1 and out of line with the rod *d*. When the carrier moves to the position shown in Fig. 1, another one of the balls rolls into position above the slide 8 ready to be projected on the next movement of the carrier.

2
Supported by the standards is a trough 23, which has an extending lip 24 projecting into the channel 6. The operator places the balls on this trough and they roll by gravity 5 into the channel. In some cases, where a number of tubes of different sizes is being made, the carrier may be designed so that the walls of the channel can be adjusted to accommodate balls of different sizes.

10 In Fig. 8, the carrier 4^a is illustrated as having a channel 6^a, the walls 25 of which are adjustable laterally and are held in the adjusted position by bolts, or other fastenings. The cover plate 26 is removable and 15 can be replaced by others of greater or less width. Other means of adjusting the mechanism to fit balls of different sizes can be used without departing from the essential features of the invention.

20 The pocket may be made separate from the carrier, as illustrated in Fig. 9, so that different pockets may be used for balls of different sizes.

25 In Fig. 6, the location of my improved mechanism is shown in relation to an ordinary tube mill.

27 is a furnace. 28 are the housings in which the welding rolls 10 and 11 are mounted. 29 is a tube trough and located 30 between my improved mechanism and the rolls 10 and 11 is a short trough 30. At the rear of the mechanism are the rollers 31, which support the rod *d* when retracted. 32 is the power driven mechanism of the 35 ordinary type for projecting and retracting the rod *d*.

40 In order to operate the mechanism for projecting the rod simultaneously with the movement of the carrier, an air valve 34 is provided, which is connected to an air supply pipe 35, and pipes 36 and 37 connected to the cylinder 12. The air valve 34 has an arm 38 connected by a rod 39 to an arm of a hand lever 40, pivoted at 41 to the housing 42 of the rod operating mechanism 32, which is driven from a motor 33 and operated by a hand lever 43 to project, or retract, the ball-carrying rod *d* in the ordinary manner.

50 The hand lever 40 has an adjustable stop 47 for the end of the rod. When the hand lever 40 is in the position shown by dotted lines, Fig. 11, the air valve 34 is open to the underside of the piston in the cylinder 12. 55 The carrier is raised and a ball drops into the socket 9 in line with the rod *d*, which is projected by the mechanism 32. The reduced portion *c* of the rod will enter the opening *b* in the ball *a* and will carry the ball to a position between the two rolls 10 and 11. When the rod has moved to its full extent, the lever 40 is lowered to the position shown in full lines in Figs. 10 and 11, the stop 47 preventing any rearward movement of the rod as the tube is being

formed over the ball, and the valve 34 is turned so that it is open to the upper side of the piston in cylinder 12. The carrier 4 will move out of the path of the tube being formed, as shown in Fig. 1. As soon as the pipe is clear of the welding rolls and with the rod loose in the pipe, the lever 40 is raised—releasing the rod *d*, and allowing it to be retracted clear of the pipe. The lifting of the lever 40 reverses the air valve 34, permitting air under pressure to enter the lower end of the cylinder 12, and raising the carrier to locate a ball in line with the rod *d*, when the above operation is repeated. The balls, as they drop from the tube, can be placed in the trough 23.

I claim:

1. The combination in a tube mill, of a pair of rolls; a rod; means for projecting the rod; and a ball-presenting device for carrying a ball into position in alignment with the rod so that, as the rod is projected, it will pick up the ball and will carry it forward to a position between the rolls.

2. The combination in an apparatus for handling the balls of a tube mill, of a standard; a carrier movably mounted thereon, said carrier having a channel for the balls and having a pocket to receive a ball; and means for moving the carrier into alignment with a rod of the mill so that each ball will be engaged by the rod and carried out of the pocket.

3. The combination in an apparatus for handling the balls of a tube mill, of a standard; a carrier pivoted to the standard; means for raising and lowering the carrier; a channel in the carrier; a pocket at the end of the channel; and means for selecting a ball from the channel and allowing it to move into position in the pocket.

4. The combination in an apparatus for handling the balls of a tube mill, of a standard; a carrier pivoted to the standard; means for raising and lowering the carrier; a channel in the carrier; a pocket at the end of the channel; and means for selecting a ball from the channel and allowing it to move into position in the pocket, said means being actuated simultaneously with the movement of the carrier.

5. The combination of a standard; a carrier pivotally mounted on the standard, said carrier having a channel for the accommodation of a series of balls; a pocket at the outer end of the channel; a slide located between the channel and the pocket; and means for raising and lowering the slide as the carrier is raised and lowered so as to select a ball from the channel and allow it to assume a position in the pocket.

6. The combination of a standard; a carrier pivotally mounted on the standard; means for raising and lowering the carrier, said carrier having a channel for balls; a

5 pocket at the end of the carrier; a slide adapted to select one of the balls from the channel and lift the ball and allow it to roll into the pocket; and a lever pivoted to the carrier and having one arm connected to the slide, the other arm of the lever extending between two bearings on the standard so arranged that when the carrier is raised, the lever will be moved on its pivot and will 10 elevate the slide.

7. The combination of a base; standards on the base; a carrier located between the standards and pivotally mounted thereon; a cylinder pivoted to the base; a piston rod 15 extending into the cylinder and connected to the carrier, said carrier having a channel in which a series of balls can be located; a pocket at the outer end of the carrier; a slide mounted in the carrier and arranged 20 to select one of the balls from the channel and allow it to roll into position in the pocket; a lever pivoted to the carrier and connected to the slide; bearings engaging the lever for operating the slide; and a

trough mounted on the carrier in line with 25 the channel.

8. The combination of a standard; a carrier arranged to be moved into and out of position in alignment with the rolls of a tube mill; a pocket at the end of the carrier for a ball; a channel in the carrier for the reception of a series of balls; the sides of said channel being adjustable to fit balls of different sizes; a removable cover plate for the channel; and means for transferring 35 a ball from the channel to the pocket.

9. The combination in a tube mill, of a pair of rolls; a rod; means for projecting the rod; a ball-presenting carrier; a cylinder; a piston therein; a stop lever for the 40 end of the rod; an air valve connected to said lever; and pipes extending from the air valve to the ends of the cylinder so that, when the stop lever is operated, the piston is raised, or lowered, in the cylinder to move 45 the carrier.

JAMES H. MATHESON.
